UNITED STATES PATENT OFFICE.

DAVID SHERWOOD KENNEDY, OF BROOKLYN, NEW YORK, ASSIGNOR TO MERGEN-
THALER LINOTYPE COMPANY, A CORPORATION OF NEW YORK.

TYPOGRAPHICAL COMPOSING-MACHINE.

1,080,348.

Specification of Letters Patent.

Patented Dec. 2, 1913.

Application filed March 20, 1913. Serial No. 684,945.

To all whom it may concern:

Be it known that I, DAVID SHERWOOD KENNEDY, a citizen of the United States, and a resident of Brooklyn, county of Kings, and State of New York, have invented a new and useful Improvement in Typographical Composing-Machines, of which the following is a specification.

My invention relates to typographical composing machines, such as linotype machines of the general organization represented in Letters Patent of the United States, No. 436,532, to O. Mergenthaler, wherein circulating matrices are released from a magazine or magazines in the order in which their characters are to appear in print and then assembled in line, the composed line transferred to the face of the mold, the mold filled with molten metal to form a slug or linotype against the matrices which produce the type characters thereon, and the matrices thereafter elevated and returned through the distributing mechanism to the magazine or magazines from which they started.

The present improvements relate more particularly to the font-distinguisher employed to prevent matrices of one font from being distributed into a magazine designed for matrices of a different font. Generally speaking, such a mechanism is shown and described in U. S. Letters Patent to F. J. Wich, No. 688,218, December 3, 1901. Ordinarily the matrices of each style or size have specially located font indicating notches at the bottom, and the font-distinguisher has a projecting finger located in advance of the distributor, to permit the passage of matrices correspondingly notched, and to arrest matrices provided with notches in a different position, all as well known in the art.

In the accompanying drawings, the invention is disclosed in preferred form, and by way of example, in connection with a style of machine employing a plurality of shiftable magazines, such for instance as is illustrated in the application for Letters Patent of John R. Rogers, Serial No. 624,426, filed May 1, 1911, and I have provided connections whereby the distinguisher is automatically adjusted to correspond to the selected magazine in operative position.

It sometimes happens that the size or style of a font of matrices in any particular

magazine is changed, or that another magazine with different matrices is substituted therefor. The matrices of the font thus substituted are of course formed with differently located notches, and I have therefore also provided means to adapt the distinguisher to these new conditions without its actual manipulation.

Obviously many changes and variations may be made in the embodiment of the invention, and in its mode of application, without departing from its scope, and generally speaking, I desire it to be understood that I do not limit myself to any specific form or embodiment except in so far as such limitations are specified in the claims.

Referring to the drawings: Figure 1 is a perspective view of a portion of a linotype machine of the character described, having my invention applied thereto; Fig. 2 is a side elevation of a portion of the distributing devices and distributor box, partly broken away, and indicates the position of the font distinguisher; Fig. 3 is a transverse vertical section, taken substantially on the line 3-3 in Fig. 2; Fig. 4 is a side elevation of the individual rotary adjusting plate, etc.; Fig. 5 is a transverse section, taken substantially on the line 5-5 in Fig. 4; and Fig. 6 is a detached view of matrices belonging to different fonts and illustrating the location of the distinguishing notches.

Referring to Fig. 1, the magazines A¹, A², A³ are mounted in the shift frame A, and are also detachably arranged, substantially in the same manner as presented in the Rogers application previously referred to. The font-distinguisher B, provided with the projecting finger B¹ (see also Figs. 2 and 3), is located between the distributor box C and the distributing devices, which comprise the lifting finger C¹, the rail or bar D, screws D¹, and inclined plates C². The matrices X and X¹ are moved through the box C by the transfer device C³, and thereby presented to the elevating finger C¹ mounted upon the reciprocating arm C², which finger delivers the matrices to the other distributing devices, all in the customary manner. The font-distinguisher B and its finger B¹ are adjustably mounted in the cross-piece C⁴ of the box C, immediately in advance of the lifting finger C¹, and in such position as to prevent the delivery of the matrix to the finger, unless the notch therein corresponds

in position to that of the finger B^1 . Fig. 6 shows two matrices X and X^1 of different fonts and formed with the differently located notches Y and Y^1 , it being apparent that if the finger B^1 be set to correspond to the notch of one of these matrices it will prevent the lateral passage thereover of the other. The distinguisher B is formed at one end with the button B^3 , between which and the piece C^4 is mounted the spring B^2 , so as normally to hold the finger B^1 in its extreme outward position. To effect the automatic adjustment of the distinguisher B and its finger B^1 to correspond to the particular magazine in operative position, I preferably employ the arm E^1 pivotally mounted at E in the main frame and provided with an extended arm E^2 beyond the pivot, the two arms constituting a lever. The arm E^2 is so shaped and located as to be in the path of the operating abutments G mounted upon the piece F which is connected by the bracket A^{10} to the magazine shift frame A . As the magazines are moved so as to bring one or another of them into operative position, the corresponding abutment G acts upon the arm E^2 so as to vary the position of the arm E^1 , which is provided with the contact screw B^4 and the adjusting nut B^5 . The screw B^4 rests against the button B^3 of the distinguisher B , which is therefore moved in one direction by the spring B^2 , and in the opposite direction by the screw, so as to bring the finger B^1 into proper position to register with the notches of the particular matrices in action.

The parts so far described automatically effect the adjustment of the distinguisher to correspond to the magazine in operation. As previously pointed out, it also happens that from time to time the size or style of the matrices in a particular magazine is changed, or that another magazine with entirely different matrices is substituted therefore, and therefore provision is also made to compensate for such substitutions, or in other words, so that the font-distinguisher will be adjusted to correspond exactly to the notches of any given font. To this end I preferably make the operating abutments G adjustable, and in the specific form shown and described, they are polygonal plates eccentrically mounted on the piece F by means of screw-bolts G^1 . Registering holes G^3 are formed about each pivotal bolt G^1 to engage and hold the pin G^2 projecting from the plate G . In the form illustrated, the plate G is laterally movable with relation to the pivotal bolt G^1 , a spring G^4 being employed to hold the plate in its normal operative position and to insure the engagement of its pin G^2 in one of the holes G^3 , the spring also permitting the outward lateral movement of the plate and its subsequent rotary adjustment to a new position. The plate G

is preferably provided about its perimeter with numerals or other characters to indicate the particular font to which the adjoining portion of the perimeter corresponds, and thereby enables it to be adjusted readily to any desired position. Obviously such individual adjusting means, to correspond to any particular substituted font, could be employed in connection with interchangeable magazines irrespective of the specific form illustrated by way of example, wherein the magazines themselves are shifted bodily into and out of operative relation to the other parts. Also as previously pointed out, many other modifications and variations will suggest themselves to those skilled in the art and still be comprised within the spirit of my invention.

Having thus described my invention, its construction and mode of operation, what I claim and desire to secure by Letters Patent of the United States is as follows:

1. In a typographical composing machine, the combination of a plurality of shiftable magazines, a font-distinguisher, and mechanism for automatically adjusting the font-distinguisher to correspond with the magazine in operative position, the said adjusting mechanism comprising means shiftable at will to correspond to different styles of type or matrices in the selected magazine and thus to vary the extent of the adjustment.

2. In a typographical composing machine, the combination of a plurality of shiftable magazines, a font-distinguisher, a mechanism for automatically adjusting the font-distinguisher to correspond with the magazine in operative position, the said adjusting mechanism comprising an eccentrically-mounted polygonal contact plate G rotatable at will to correspond to different styles of type or matrices in the selected magazine and thus to vary the extent of the adjustment.

3. In a typographical composing machine, the combination of a plurality of shiftable magazines, the adjustable font-distinguisher, and connections actuated by the shifting of the magazine to adjust the font-distinguisher, the said connections comprising the rotatable eccentrically-mounted polygonal plate G .

4. In a typographical composing machine, the combination of a magazine for the type or matrices, a font-distinguisher, and mechanism for automatically adjusting the font-distinguisher, the said adjusting mechanism comprising also shiftable means that may be manipulated at will to adapt said mechanism to the particular style or font of the type or matrices contained in the magazine.

5. In a typographical composing machine, the combination of a magazine for the type or matrices, a font-distinguisher, and mech-

anism for automatically adjusting the font-distinguisher, the said adjusting mechanism comprising an eccentrically-mounted polygonal contact plate G rotatable at will to 5 correspond to the particular style or font of the type or matrices contained in the magazine.

6. In a typographical composing machine, the combination of a magazine, a font dis-10 tinguisher and mechanism for automatically adjusting the same to correspond to the magazine, the said mechanism including

means to vary the extent of adjustment of the font distinguisher to correspond to different fonts of type or matrices in said 15 magazine.

In testimony whereof I hereunto set my hand this 16th day of March, 1912, in the presence of two attesting witnesses.

DAVID SHERWOOD KENNEDY.
